UNITED STATES PATENT OFFICE

HENRY KIELBERG, OF MARTINS FERRY, OHIO, ASSIGNOR TO WHEELING STEEL CORPORATION, OF WHEELING, WEST VIRGINIA, A CORPORATION OF DELAWARE

SHEET METAL PACKAGE

Application filed September 28, 1929. Serial No. 395,885.

This invention relates broadly to sheet metal containers or packages of that type in which nested sections or joints of stove pipe are packed for shipment and storage, and it has for its primary object to provide a package of this character having an end closure and provided with novel and inexpensive means whereby said closure may readily and conveniently be rendered removable.

10 In describing the invention in detail, reference is herein had to the accompanying drawings, in which—

Figure 1 is a view partly in side elevation and partly in section of an end portion of my container as it appears prior to turning the terminal edge of said portion into securing relation to the closure;

15 Figure 2 is a section on line 2—2, Fig. 1, following the turning of said edge into closure securing position;

Figure 3 is an end elevation of the package with the end closure in place;

20 Figure 4 is a section on line 4—4, Fig. 3; and

25 Figure 5 is a side elevation of the end portion of the package illustrating the use of the tearing member, or strip.

Referring to said drawings, 1 designates the body of the container which is made of 30 light gauge sheet metal, preferably soft iron or unannealed steel, and which possesses tubular form with an end open to permit of the introduction therein of the nested joints of stove pipe or other material to be transported.

35 Provided in said body at a suitably spaced distance from the terminal edge of the metal of said open end, as will hereinafter be explained, and located adjacent to the usual side seam 2 of said body, is a small slot or 40 aperture 3 through which is projected the free end 4^a of a narrow member, as the sheet metal strap 4. This member, which may, if preferred, be provided in the form of a length 45 of wire, is introduced between the body 1 and an outwardly directed annular flange 5 formed on an end member or closure 6 when the latter is inserted within said open end of the body following introduction of the nested 50 joints. Said member 4, designed as a tearing

strip, possesses a length approximating the circumference of the tubular body 1 and has its opposite end folded back parallel to the inner side of the strap, forming a hook 7 which is disposed in locking engagement with the closure, being seated in an open slot, notch or recess 8 provided therefor in the closure flange 5, as shown in Figs. 1 and 2.

55 In closing the end of the package, the end 4^a of the member 4 is first projected outward through the aperture 3, following which the tearing member is laid within the close embrace of the body 1. The hook end 7 of said member is then held slightly elevated while the closure 6 is inserted to a position wherein it seats upon the adjacent ends of the nested stove pipe (not shown) contained by said body and it is so disposed that the slot 8 of its flange 5 is located closely adjacent to the position of the body seam 2, as is clearly shown in Fig. 2, following which said hook end is dropped into said slot 8. The terminal edge 1^a of the open end of the container body is finally turned down into interiorly seating relation to the closure flange 5, as shown in 70 Fig. 4.

75 The projecting tongue 4^a of the member 4, which may have its end received beneath, or tucked under the adjacent fold of the side seam 2 of the container body, is adapted to be utilized for effecting such mutilation of the container body as is required to admit of ready access to the contents of the latter. When such access is desired, said tongue is grasped by means of a suitable gripping 80 tool, as a pair of pliers, and the member 4 is pulled rearwardly in a direction circumferential with respect to said body to effect tearing of the metal of the latter, as shown in Fig. 5, such tearing being continued until the side 85 seam 2 is reached, thus almost completely severing from said body the inturned terminal portion by means of which the closure is retained in place. The said terminal portion may then be lifted and swung back to a position 90 wherein the end closure 6 is released, whereupon the latter may be withdrawn from the container body.

95 Due to the soft character of the metal of the container body, comparatively slight re- 100

sistance to tearing is offered when force is applied to the tearing member in the manner stated. Such tearing ordinarily occurs along two parallel lines adjacent to the opposite edges of the strap, there being thus removed ahead of the strap a narrow irregular strip 9, substantially as shown in Fig. 5.

What is claimed is—

1. A sheet metal package comprising a tubular body of readily rupturable material, having an open end, said body having an aperture therein adjacent to said end, a closure for said end having an outwardly directed annular flange provided with a recess, said closure being received within said end in a position wherein said recess is located adjacent to said aperture, and a metal-tearing member interposed between said closure flange and said body in embracing relation to the former, one end of said member having a hook end received in said recess and having its opposite end projected outward through said aperture, the extreme end of said body being turned inward into interiorly seated relation to said closure flange.
2. A sheet metal package comprising a tubular body having an open end and provided with an aperture adjacent to said end, a closure having an annular flange provided with a recess, said closure being adapted for introduction within said end with its flange extending outwardly and with said recess located adjacent to said aperture, and a metal-tearing member adapted to be positioned intermediate said body and said flange and having an end projecting outwardly through said aperture, said member having its opposite end bent back to form a hook for engaging in said recess, the extreme edge portion of said end of the body being adapted to be turned inward into interiorly seated relation to said closure flange.
3. A sheet metal package comprising a tubular body having an open end and provided with an aperture adjacent to said end, a closure for introduction within said end, said closure having an annular flange, and a metal-tearing member adapted to be closely fitted between said flange and said body in circumferential embracing relation to the former, said member having one end attached to said cover adjacent to the position of said body aperture and its opposite end projected outwardly through said aperture.

55 In testimony whereof, I affix my signature.
HENRY KIELBERG.
